OTHER PUBLICATIONS

U.S. Appl. No. 29/394,900, filed Jun. 22, 2011, entitled "Thermostat Housing".

Primary Examiner — Antoine D Davis

(74) Attorney, Agent, or Firm — Seager Tufte & Wickhem LLC

(57) **CLAIM**

The ornamental design of the thermostat housing, as shown and described.

DESCRIPTION

FIG. 1 is a perspective view of a thermostat housing;
FIG. 2 is a front elevation view of the thermostat housing of FIG. 1;

FIG. 3 is a left elevation view of the thermostat housing of FIG. 1;

FIG. 4 is a right elevation view of the thermostat housing of FIG. 1;

FIG. 5 is a top view of the thermostat housing of FIG. 1; and,
FIG. 6 is a bottom view of the thermostat housing of FIG. 1.
The portions illustrated in broken lines on the figures are for
illustrative purposes only and form no part of the claimed
design.
